UNITED STATES PATENT OFFICE.

PETER MORA, OF CLINTON, INDIANA.

ACETYLENE-LAMP.

1,226,237.

Specification of Letters Patent.

Patented May 15, 1917.

Application filed November 18, 1916. Serial No. 132,080.

To all whom it may concern:

Be it known that I, PETER MORA, a subject of the King of Italy, residing at Clinton, in the county of Vermilion and State 5 of Indiana, have invented certain new and useful Improvements in Acetylene-Lamps, of which the following is a specification.

This invention relates to certain new and useful improvements in acetylene lamps.

10 The primary object of the invention is the provision of an acetylene lamp adapted for burning gas generated by carbid, a pilot light being arranged for initially starting the main burner, a single moisture receptacle being provided for the pilot light and burner.

A further object of the invention is the provision of an acetylene gas generator having a single burner supplied with gas under 20 regulation from a plurality of carbid holders of different dimensions, a single water tank being provided for said holders, the supply of water to the latter being individually controlled.

25 A still further object of the device is the provision of a gas generator having a water holder and two separable carbid holders all compactly arranged whereby a single burner is provided with gas from either or both of 30 said holders.

In the drawings forming a part of this application and in which like designating characters refer to corresponding parts throughout the several views:—

35 Figure 1 is a side elevation of the device.

Fig. 2 is a front elevation thereof.

Fig. 3 is a central longitudinal sectional view of the same.

Fig. 4 is a top plan view of the invention.

Fig. 5 is a central longitudinal section of the device taken in a different plane from the line of section of Fig. 3.

Fig. 6 is a transverse sectional view taken 45 upon line VI—VI of Fig. 5.

Fig. 7 is a perspective view of the moisture conducting wire for the main carbid container.

Fig. 8 is a similar view of the tubular 50 controlling valve therefor.

Fig. 9 is a perspective view of the needle valve for the auxiliary container.

Fig. 10 is a perspective view of a guide member employed with the auxiliary container.

Fig. 11 is an inverted perspective view of the same.

Fig. 12 is a perspective view of the auxiliary container.

Fig. 13 is an inverted perspective view 60 thereof.

Fig. 14 is a perspective view of a packing disk employed, and,

Fig. 15 is an inverted perspective view of 65 the said disk.

The present lamp broadly consists of a water receptacle 10 arranged at the top thereof and having a burner 11 arranged at one side thereof adapted to be supplied with a combustible gas from a main container 12 70 and an auxiliary container 13 arranged beneath the receptacle 10 and supplied with water from the latter under suitable regulation.

An inverted bowl-shaped casing 14 is carried by the bottom 15 of the receptacle 10 extending partly within the said receptacle while a sleeve 16 depends axially within the casing 14. A water supply tube 17 extends through the sleeve 16 communicating with 80 the interior of the receptacle 10 and provided with a valve seat 18 upon its upper end while the lower end of the tube 17 is arranged within the main container 12.

A tubular valve 19 extends through the 85 receptacle 10 having screw-threaded attachment with a bushing 20 in the upper side of the receptacle whereby the lower end of the valve 19 is readily adjusted with respect to the valve seat 18 under the control of a turn 90 handle 21 at the outer end of the valve exteriorly of the receptacle. A feed wire 22 for the water formed of flexible material is longitudinally shiftably arranged through the valve 19 and the tube 17 whereby the 95 passage through the said valve and tube may be readily cleaned, it being understood that by elevating the valve 19 the water is allowed to pass from the receptacle through the valve seat 18 and tube 17 into the main 100 container 12, the relative diameters of the wire 12 and tube 17 being so formed as to accommodate such passage for the water without allowing gas from the container 12 to escape through the said pipe 17.

105 A water feed pipe 23 is provided in the sleeve 16 communicating with the receptacle 10 and terminating at 24 opening into the auxiliary container 25 adapted to be positioned upright within the casing 14, as best 110

shown in Fig. 5 of the drawings. A needle valve 26 extends through the receptacle 10 at the upper end of the pipe 23, it being understood that the lower free end of the 5 needle valve extends entirely through the said pipe for the purpose of maintaining the same free for passage of fluid from the receptacle 10 to the auxiliary container 25, a turn knob 30 being arranged upon the upper 10 end of the needle valve 26 for operating the latter.

A guide member 31 is provided having a tubular portion 32 surrounding the sleeve 16 and arranged with a port 33 adjacent the 15 end 24 of the water pipe 23. The auxiliary container 25 has a bottom opening 34 adapted for receiving the tube 17 when the auxiliary container is operatively positioned, a packing disk 34 being then slidably arranged over the tube 17 which latter extends through the central bore 35 of the disk while an exteriorly threaded boss 36 is carried by the said disk having threaded engagement with the interior of the sleeve 16. An annular bead 37 is provided upon the auxiliary container 25 adapted for supporting a washer 38 between the said bead and an annular shoulder 39 of the casing 14, which taken together with the packing disk 34 20 seals the auxiliary container 25 within the casing 14 against all communication excepting with the water pipe 23 and a curved burner tube 40 carried by the top of the casing 14 forming a part of the aforementioned 25 burner 11. Lugs 41 are carried by the bottom of the disk 34 whereby the disk may be tightly seated against the bottom of the auxiliary receptacle and it will be noted that the upper free end of the tubular portion 32 30 of the guide 31 has a tight frictional engagement with the sleeve 16 while guide ears 42 and a depending flange 43 of the auxiliary container 25 are adapted for the accommodation of the packing disk 34.

45 The main container 12 has a tubular flange 44 adapted for threaded engagement with a lower extension 45 of the casing 14 and whereby the said main container is secured to the said casing beneath the auxiliary container 25, a flexible packing 46 being 50 preferably arranged between the said extension and flange. A hinged inlet door 47 is carried by the top of the receptacle 10 whereby a supply of water such as 48 is maintained within the said receptacle. The gas conducting pipe 40 of the burner 11 has 55 an outlet nipple 48' adjacent the forward side 49 of the receptacle while a protecting annulus 50 is carried by the said side surface 60 rounding the burner. A gas conducting passage 51 is provided between the main container 12 and a burner pipe 40 with which it communicates, such passage being arranged through an elbow 52 beneath the annulus 50 and receptacle 10. A pin valve 53

is provided for the passage 51 whereby the gas from the main container 12 is suitably regulated in its passage to the burner 11. A suitable straining medium 54 may be arranged in the burner pipe 40 if desired while a handle 55 is provided upon the rear end of the receptacle 10. It is understood that a supply of carbide 56 is arranged within the auxiliary container 25 while carbide 27 is also positioned within the main container 12. By opening the needle valve 26 some of the water 48 passes into the auxiliary container and the gas generated thereby passes through the burner tube 40 and nipple 48' where the same may be lighted within the annulus 50. The supply of gas from the said auxiliary container 25 will continue to be fed to the burner 11 until exhausted under the regulation of the water supply needle valve 26, such supply being maintained as a small pilot light if desired. Water from the receptacle 10 is allowed to pass through the tube 17 into the carbide 57 of the main container 12 suitably regulated by the tubular valve 19 and the gas so generated passes through the conduit 51 to the burner tube 40 under the regulation of the pin valve 53, it being understood that such gas will be lighted by the pilot light when passing through the nipple 48' as such gas from the main container augments that passing from the auxiliary container. After the main supply of gas is lighted, the needle valve 26 may be closed for discontinuing the generation of gas in the auxiliary container 25 or such supply may be continued from the auxiliary container regulated by the said needle valve and in which event the carbide in both containers will be supplying gas to the burner 11. An acetylene burner is provided in which a small pilot may be maintained constantly burning if desired, it being understood that upon closing the pin or valve 53, the gas from the auxiliary container 25 still remains lighted while the device may also be employed for the generation of gas from the two containers either 95 successively or simultaneously.

What I claim as new is:—

1. An acetylene gas lamp comprising a 115 water receptacle, an inverted bowl-shaped casing arranged within the bottom of said receptacle, a sleeve axially arranged within said casing, a water supply pipe terminating within said sleeve communicating with said receptacle, a guide member having a tubular portion frictionally arranged over the said sleeve and having an outlet port communicating with the open end of the said pipe, an auxiliary container arranged within the 120 said casing, a packing disk engaging the said container threaded into the said sleeve, a needle valve extending through the said receptacle having its lower end movably arranged within the said pipe, a turn knob 125 130

upon the upper end of the said valve, a curved gas outlet tube carried by the said casing extending through the said receptacle projecting exteriorly thereof.

- 5 2. An acetylene gas lamp comprising a water receptacle, an inverted bowl-shaped casing arranged within the bottom of said receptacle, a sleeve axially arranged within said casing, a water supply pipe terminating within said sleeve communicating with said receptacle, a guide member having a tubular portion frictionally arranged over the said sleeve and having an outlet port communicating with the open end of the said pipe, a turn knob upon the upper end of the said valve, a curved gas outlet tube carried by the said casing extending through the said receptacle projecting exteriorly thereof, a protecting annulus carried by the said receptacle surrounding the projecting free end of the burner tube, a main container positioned in axial alinement to the said casing removably secured to the latter, a valved gas communicating means between the said main container and said burner tube within the annulus, and water supply means for the said main container.
- 10 3. An acetylene gas lamp comprising a water receptacle, an inverted bowl-shaped casing arranged within the bottom of said

receptacle, a sleeve axially arranged within said casing, a water supply pipe terminating within said sleeve communicating with said receptacle, a guide member having a tubular portion frictionally arranged over the said sleeve and having an outlet port communicating with the open end of the said pipe, an auxiliary container arranged within the said casing, a packing disk engaging the said container threaded into the said sleeve, a needle valve extending through the said receptacle having its lower end movably arranged within the said pipe, a turn knob upon the upper end of the said valve, a curved gas outlet tube carried by the said casing extending through the said receptacle projecting exteriorly thereof, a protecting annulus carried by the said receptacle surrounding the projecting free end of the burner tube, a main container positioned in axial alinement to the said casing removably secured to the latter, a valved gas communicating means between the said main container and said burner tube within the annulus, a water tube extending through the said sleeve terminating within the main container with its upper end forming a valve seat within the receptacle, a tubular valve threaded to the receptacle positioned upon the said seat when the valve is closed, and a flexible cleaning wire longitudinally shiftably arranged through the said tubular valve and water supply tube of the main container.

In testimony whereof I affix my signature. 70

PETER MORA.
